UNITED STATES PATENT OFFICE.

CHARLES VOLUNTEER BOSSERT, OF NEW YORK, N. Y., ASSIGNOR TO LOUIS BOSSERT & SONS, INC., OF NEW YORK, N. Y., A CORPORATION OF NEW YORK.

PORTABLE HOUSE.

1,249,011.

Specification of Letters Patent. Patented Dec. 4, 1917.

Application filed March 20, 1915. Serial No. 15,707.

To all whom it may concern:

Be it known that I, CHARLES V. BOSSERT, residing at and whose post-office address is 1281 Carroll street, of the city of New York, in the county of Kings and State of New York, have invented certain new and useful Improvements in Portable Houses; and I do hereby declare the following to be a full, clear, and exact description of the invention, such as will enable others skilled in the art to which it appertains to make and use the same.

The object of my invention is to provide certain improvements in portable houses, that is, houses formed of a plurality of sections adapted to be readily dismantled for transportation and assembled at their destination. I provide simple and efficient means for locking the sections at the joints without using nails or screws, and also for preventing leakage.

In the accompanying drawing Figure 1 is a vertical transverse sectional view. Fig. 2 is a horizontal sectional detail of the joint between the siding sections; Fig. 3 a longitudinal sectional detail of the manner of connecting the roof sections; Figs. 4, 5 and 6 various forms in which the meeting edges of the metal covering of the roof sections may be united; Fig. 7 a section of the joint between the floor beam and the sill; Fig. 8 a similar view of the connection between the ridge pole and the gable end, and Fig. 9 a fragmentary detail of the parts shown in Fig. 1.

I have illustrated the general formation of the house in conventional design having sides 2 supporting a gable roof 3 and ridge pole 4. It will be understood that the sides and the roofing and flooring are each made up of a series of sections connected together. Therefore a detail illustration and description of the manner in which one side section is secured to the adjacent section and to the floor beams and roof will suffice without repetition as to all of the corresponding joints, and the same is true as to the roof sections.

I will first describe the connection between the side sections and the roof. Extending along the top of these side sections is a rail 5 formed in its upper face with a double bead 6 and a groove 7. A wall plate 8 is supported on the rail 5 and its lower edge is formed with a double groove 9

adapted to receive the double bead 6 of rail 5 and also with a groove 10 adapted to register with groove 7. As illustrated in Fig. 1, the wall plate 8 is wider than rail 5 so as to bring its outer face flush with the weather boarding 12. By the construction described any dampness that may find its way between the rail and wall plate will enter the drip channel formed by the grooves 7 and 10 which intersects a similar drip channel vertically arranged in the meeting edges of the side sections. The double bead and groove connection 6, 9, not only insures a tight joint as against lateral displacement but renders the joint virtually air and water proof.

Extending vertically through the rail and wall plate at their points of connection with the roof, is a bolt 13 having an angular portion 14 extending through the meeting or adjacent stiles 15 of two roof sections. See Figs. 1 and 9.

In Fig. 2 I have shown the connections between the sections forming the sides. This is the same as the described connection between the sides and the roof in that the double bead and groove formation is maintained and the drip channel 16 intersects the horizontal drip channel 7. The meeting rails 17 are secured together by bolts 18.

The preferred manner of connecting the roof sections is illustrated in Fig. 3, where 20 is the roof proper and 21 the ceiling, providing an intermediate air space, and 22 and 23 the meeting stiles. As illustrated the stile 22 is rabbeted to receive the stile 23, the interlocking portion being formed at an acute angle 24. The adjacent faces of the stiles 23 and 24 are slightly spaced apart above the rabbeted portion as at 25 and at the bottom of this spaced apart portion is a drip channel 26. The space 25 is adapted to contain the meeting edges of the tin or other metal with which the roof sections may be covered. As illustrated in Fig. 4 the meeting edges of the metal 27 may be simply turned to form angular extremities extending into the space 25 or one of them may be lapped over the other as in Fig. 5, or they may be connected by a double lap joint as in Fig. 6. A bolt 28 is shown connecting the two stiles. In assembling the roof sections when the meeting edges of the tin are formed as in Fig. 4 the sections may be simply placed down side by side. When these edges are formed as in Figs. 5 or 6 the

first section is put in position and the second section placed at the end edge thereof to move along the same longitudinally so as to effect the proper engagement of the interlocking extremities.

The roof sections are connected together at the ridge pole 4 by a bolt 30, Fig. 1, one roof section being preferably rabbeted to receive the angular face of the other. I have shown a metallic strip 31 extending over the meeting edges of the roof sections and covering the bolt and connected to the tin roofing by lap joints 32.

In Fig. 7 I have shown the construction by which the floor beams and sills are secured together. The sills 33 are shown formed with vertically arranged circular recesses 34 contracted at the face of the sill as at 35. The floor beam 36 is formed with reduced portions 37, constituting shoulders to bear against the outer face of the sill and an extremity 38 substantially circular in cross section adapted to fit within the circular recess 34. The extreme end of the floor beam is preferably flattened as at 39 to allow a reasonable degree of play and to prevent the parts from binding. After the sills are in position the floor beams are inserted by sliding them into the sills. The sills being wider than the floor beams their recesses extend downward only sufficiently far to hold the floor beams in the correct position.

In Fig. 8 I have shown the manner of securing the ridge pole to the gable ends by an

angular bolt 13' substantially the same as 35 shown in Figs. 1 and 9.

I claim as my invention:—

1. A portable house having a rail extending along the top of its side sections, said rail having a double bead and a groove 7 in 40 its upper face, and a wall plate on said rail and formed with a double bead and a groove 10 adapted to register with said former groove to form a drip channel and drip channels in said side sections communicating 45 with said former channel.

2. In a portable house, side sections having drip channels adjacent their vertical meeting edges, and a rail extending along the top of said side sections, a drip channel 50 being formed in said rail and intersecting said first mentioned channel.

3. In a portable house, roof sections having stiles, the outer face of one stile being rabbeted at an acute angle as at 24 to receive an adjacent stile, a space being provided above said rabbet, metal coverings for said roof sections, the meeting edges of said coverings being united and held within said space, and a drip channel at the inner end 60 of said space.

In testimony whereof, I have signed this specification in the presence of two subscribing witnesses.

CHARLES VOLUNTEER BOSSERT.
